UNITED STATES PATENT OFFICE.

HARRY E. HARBAUGH, CHARLES FRANK BUQUO, AND GEORGE F. SPAETH, OF CINCINNATI, OHIO; SAID BUQUO AND SAID SPAETH ASSIGNORS TO SAID HARBAUGH.

MOVING-PICTURE-FILM PROTECTOR.

Application filed April 24, 1919. Serial No. 292,347.

To all whom it may concern:

Be it known that we, HARRY E. HARBAUGH, CHARLES FRANK BUQUO, and GEORGE F. SPAETH, citizens of the United States, residing at Cincinnati, in the county of Hamilton and State of Ohio, have invented certain new and useful Improvements in Moving-Picture-Film Protectors, of which the following is a specification.

Our invention relates to moving-picture apparatus and its object is to provide simple and reliable means to prevent ignition of or other damage to films when broken or obstructed during their operation, especially when driven by an electric motor.

Our invention consists in the combination of parts and in the details of construction and arrangement of parts as will herein-after be more fully described and claimed.

In the drawings:

Fig. 1 is a side elevation representing diagrammatically a moving-picture projecting apparatus with our invention applied thereto, the apparatus being represented by dotted lines only, and our invention being shown in full lines;

Fig. 2 is a perspective view of part of the apparatus showing more clearly how our invention is combined therewith, the cover for the switch parts being represented by dotted lines;

Fig. 3 is a side elevation of the switch, the cover being shown in vertical cross-section;

Fig. 4 is a horizontal longitudinal section of the same on a plane corresponding to the line 4-4 of Fig. 3;

Fig. 5 is a vertical longitudinal section of the same on a plane corresponding to the line 5-5 of Fig. 3;

Fig. 6 is a vertical cross-section through the switch rotor on a plane corresponding to the line 6-6 of Fig. 5;

Fig. 7 is a view similar to Fig. 1 showing a modification of our invention as applied to a different type of moving-picture projecting apparatus;

Fig. 8 is a front elevation of the switch of this modification, the cover being shown in section; and

Fig. 9 is an interior side elevation of the same with the cover shown in section.

As shown in Figs. 1 to 6, inclusive, our invention is applied to moving-picture pro-

jecting apparatus which is well-known in the art, and in which the film 1 passes down over a roll 2 on the side thereof toward the lamp-house with the loop 3 of the film on the other side toward the screen; the film 1 being wound from the upper reel 4 to the lower reel 5 under the action of the motor 6 and suitable transmission mechanism 7, as is well-known in this kind of machines. The operation of the motor is controlled as usual by the switch 8 in the control or switch-box 9 on the side of the apparatus.

On the front of the lamp-house 10 is the condenser-hood 11.

All of the above is well-known and is described only to facilitate the following description of our invention which comprises the novel switch or circuit-breaker 12 governed by the part of the film below the lower sprocket or roll 2 and by the loop 3 thereof, and an electro-magnetically controlled dowser 13 in series with the switch or circuit-breaker 12 and with the motor 6.

The present invention is broadly the same as that disclosed and claimed in Patent No. 1,200,938, issued October 10, 1916, on the invention of Harry E. Harbaugh, et al. It differs specifically from the invention there-in disclosed in the improved construction and arrangement of the circuit-breaker or switch mechanism and in the improved combination thereof with a dowser herein represented as the dowser 13 similar to that of the aforesaid patent; but which dowser, it will be understood, may be of any practical kind capable of operating in conjunction with our improved circuit-breaker or switch mechanism.

This switch 12 of Figs. 1 to 6, inclusive, comprises the rotor 14 which is made up of a pair of insulating disks 15 and a contact member 16 between the two disks 15; these disks and member being fixed together by rivets 17 (Fig. 6). The insulating disks 15 have relatively small central openings fitting snugly around the shaft 18 whereby the rotor is concentrically mounted on the shaft and capable of rotation relatively thereto. Each disk also has, opening into this central opening, a recess 19; and the shaft 18 has fixed to it a hub 20 with a pin 21 fixed in the hub and projecting parallel with the shaft 18 into the recesses 19 of the disks

15. The contact member 16 has the central opening 22 amply large and with a recess 23 adjacent to the disk recesses 19 and pin 21 so that there will be no chance of electrical contact or arcing between the contact member 16 and the metal of the shaft 18, hub 20 and pin 21. The recesses 19 are a little wider than the pin 21 so that a slight amount of rotation of the shaft 18 is permitted in either direction before it begins to rotate the rotor 14 made up of the disks 15 and member 16 as before described.

10 The shaft 18 projects some distance past the face of the rotor, which is the side of the rotor opposite from that where the hub 20 is; and a light helical spring 24 is coiled around the shaft 18 and compressed between this face of the rotor and a washer 25 held on the end part of the shaft 18 by a cotter pin 26.

15 The switch-plate 27 is a flat upright member with a flange 28 projecting out under the rotor 14 at the bottom and with a pair of upwardly opening channels 29 inclined downwardly and outwardly on which is clamped a yoke 30 with corresponding downwardly opening channels. These receive the cables 31 and 32 which carry the conductors to be connected by the switch 25 as will hereinafter be more fully described.

20 This switch-plate 27 also has at its top, projecting out over the rotor 14, a lug 33. The casing or cover 34 is a rectangular box with one side and its bottom open and fits 35 onto the switch-plate 27 with its top screwed to the lug 33. The frame 35 comprises the elongated main horizontal part 36 and the upwardly and downwardly extending flanges 37 and 38 at one end, to which the switch-plate 27 is fastened by screws 39 passing in 40 from the face of the switch-plate in which face the heads of the screws are countersunk.

25 The insulating plate 40 is flat and rectangular and has the left and right contact pieces 41 and 42 fastened to its face by means of screws 43 and 44 passing through the insulating plate from the back thereof into the pieces 41 and 42 below and above, respectively. The upper screws 44 project 30 out past the fronts of the pieces 41 and 42 and thus form studs on which are screwed the knurled binding nuts 45. A thin sheet of insulating material 46 is secured to the back of the insulating plate 40 across the heads of the screws 43 and 44, and this insulating plate 40 is fastened to the face of the switch-plate 27 with this insulating sheet 46 coming between it and the plate 27, by means of screws 47 passing 35 through from the face of the insulating plate respectively above and below the rotor 14. Each contact piece 41 and 42 comprises a contact face 48 and 49, respectively over adjacent to the rotor 14 where the respective arms 50 and 51 of the rotor contact member 16 will make contact with them simultaneously as the rotor comes into position with said arms 50 and 51 horizontal. Each one of these arms 50 and 51 is of tapered outwardly opening channel formation with its back slightly rounded at its upper and lower edges; and the contact faces 48 and 49 are also somewhat rounded or sloped at their upper and lower ends.

40 Each one of these contact pieces 41 and 42 also comprises a downwardly projecting lug 43' and an upwardly projecting lug 44' lying flat against the face of the insulating plate 40 to afford ample strength and stability to the respective contact piece 41 or 42, and also to give ample electrical conductivity thereto.

45 The cable 31 contains the conductors 52 and 53 and the cable 32 contains the conductors 54 and 55. Two of these conductors 53 and 54 are continuous at A inside the cover or casing, and the conductor 52 is clamped under the nut 45 of the contact piece 41 and thus electrically connected thereto; while the other conductor 55 is similarly connected to the other contact piece 42.

50 The dowsing 13 as here shown is similar to that disclosed and claimed in the aforementioned patent in that it comprises the electro-magnet 56 fixed on the top of the condenser-hood 11 with its core 57 extending horizontally, and a shutter 58 pivoted transversely in a bracket 59 fastened to the front end of the hood 11. This shutter 58 normally projects horizontally above the front of the hood 11 and has an armature 60 which then extends upward substantially at right angles to the shutter 58 which, by being attracted to the core 57 of the magnet 56, causes the shutter 58 to be held up in this position, thus allowing the light and heat rays to pass from the condenser-hood 11 through the film 1 and the other parts of the apparatus, including the shutter 61, to project the image on the screen, as is well-known. This condition is maintained as long as the magnet 56 is energized by current flowing through its coils; but the instant that the current therethrough is interrupted it releases the shutter 58 to drop in front of the hood 11 and immediately cut off the light and heat rays from the film 1, as is fully described in the aforementioned patent. The current for this is derived from the same source as is the current for operating the motor 6. As here shown the conductor 52 leads to one end of the coil of the magnet 56 and the conductor 53 leads from the other end of the said coil, while the conductor 54, continuous with the conductor 53, leads to one bar of the switch 8; the other bar being connected by means of the conductor 62 with one terminal of the motor 6. These bars of the switch connect, when the switch is closed,

with the respective leads 63 and 64 from a suitable source of current. The other conductor 55 leads to the other terminal of the motor 6. It will be understood that these conductors are arranged with their relation to the switch 12 as shown merely for convenience in wiring; since a single cable with two conductors may be cut open and one of its conductors parted, and the parted ends clamped by the nuts 45 as before described.

The shaft 18 has a bearing in a hub 65 integral with the switch-plate 27 and occupying an opening in the insulating plate 40, and this shaft 18 extends through the upper flange 37 of the frame 35 and along above the main part 36 of said frame into a bearing 66 projecting up from said part 36 near the other end thereof. A collar 67 fixed to the shaft 18 at the far side of this bearing 66 cooperates with the hub 20 in limiting end play of the shaft 18. Over near the switch parts this frame part 36 has the downwardly projected lug 68, and at its other end past the bearing 66 has the downward projection 69 through which a set screw 70 passes inwardly toward the lug 68. A platen 71 has parallel studs 72 sliding in openings in the projection 69 at the opposite sides of the screw 70 and is forced inward by the set screw 70. By means of these and the lug 68, the frame is clamped on the bed plate of the projecting apparatus on top of its lower film magazine just to the rear of the film actuating mechanism, as clearly shown in Fig. 2. The platen 71 preferably has a slight inwardly turned bead 73. This platen thus prevents marring of the side of the bed plate, and also effectively prevents slipping up of this end of the frame therefrom.

Thus mounted, the switch or circuit-breaker mechanism just before described lies on the side of the apparatus away from the usual position of the operator, with the shaft 18 projecting over toward the operator's side into its bearing 66. Just inside this bearing 66 an arm 74 is mounted on the shaft 18 and held fast thereto by a set screw 75 in such a position that it projects upwardly and over toward the aforesaid stretch of film 1 below the lower roll or sprocket 2. Near the free end of this arm 74 a stud 76 projects in and carries an idler roller 77 to rotate on the stud while bearing against said stretch of film. A set screw 78 holds this stud 76 fast in the arm 74. The relative positions of the arm 74 and the switch or circuit-breaker rotor 14 on the shaft 18 are such that, when the film 1 has its normal tension, the rotor 14 will be held so that the contact arms 50 and 51 make full connection with the contact pieces 41 and 42 in the middle of the respective contact faces 48 and 49 thereof. Thus, un-

der normal conditions, electrical connection will be maintained between the two conductors 52 and 55. Any lessening of the tension of the film 1 in the stretch where the roller 77 bears thereon, removing the support thus afforded to the arm 74, will result in a falling of the arm 74 on account of its own weight and that of the parts carried on the arm. If this lessening of tension is only slight, as is constantly occurring in the normal operation of the film, there will be no material rotation of the rotor 14 on account of the loss of motion between the shaft 18 and said rotor 14, permitted by the play of the pin 21 in the recesses 19 of the rotor insulating disks 15. But when such a slackening occurs as is caused by some serious derangement or obstruction of the film 10, resulting in its stoppage in the line of projection long enough to become ignited, a large degree of lowering of the arm 74 will be permitted. Then the shaft 18, through its pin 19 engaging with the rotor insulating disks 15, will turn the rotor 14 so far around that its arms 50 and 51 will ride down off the contact faces 48 and 49.

This rotor 14 is kept in contact with these faces 48 and 49 by the pressure of the spring 24; and the rounding of the adjacent faces of the arms 50 and 51 and the sloping of the terminal parts of the faces 48 and 49 results in a tendency for this spring 24 to force the arms off the faces 48 and 49. This tendency becomes stronger as the arms approach these terminal parts of the faces 48 and 49; and when they reach these terminals the spring 24 is enabled, due to the wedging effect thus afforded by the sloping faces of the contacting parts, to impel the rotor arms 50 and 51 quickly away from the faces 48 and 49, and thus abruptly accomplish a comparatively wide separation of the hitherto electrically contacting parts, and thereby minimize arcing so as to almost completely avoid burning of the contact surfaces when breaking the circuit.

It will be understood that when the circuit is thus broken, the shutter 58 of the dowser 13 falls, as before described, and the device operates substantially as fully set out in the aforementioned patent.

In the kind of projecting apparatus taken for example in Figs. 1 to 6, there is a device commonly known as a "loop setter." It comprises an idler roller 79 just below and forwardly of the lower sprocket or roll 2, inside the loop 3 of the film 1, and also comprises a clutch device 80 on the rear end 120 of the shaft of the lower sprocket or roll 2, and suitable mechanism connecting this idler roller 79 and this clutch mechanism 80 so that any material shortening of the loop 3, and consequent pulling of the shortening 125 loop upward on the roller 79, operates the

clutch 80 to disconnect the lower sprocket or roll 2 from the driving mechanism of the machine; this unconnected condition prevailing until other parts of the machine, 5 continuing to operate normally, have lengthened the loop 3 and permitted the roller 79 to drop, whereupon the clutch mechanism 80 is permitted to restore the operative connection between the lower sprocket or roll 10 2 and the rest of the mechanism, and the machine continues in its normal operation. This loop-setting device is very efficient for 15 this purpose; but frequently results in a slackening or stoppage of the film so as to endanger it in the intense heat from the lamp. It is thus highly desirable that the 20 dowser 13 should be made to cut off the heat and light rays during any excessive conditions of this kind incident to the operation 25 of loop-setting.

We combine with the aforescribed switch or circuit-breaker mechanism, additional mechanism operating in conjunction with the loop-setter to cause a breaking of 25 the circuit by the aforesaid mechanism at each operation of the loop-setter.

As here shown the main part 35 of the frame 36 has, projecting toward the film actuating apparatus, a bracket 81, and a stand- 30 ard 82 has a base 83 fixed to this bracket 81 and carries at its upper end a horizontal bearing 84 for a lever 85 that projects over into the annular groove of the clutch mechanism 80, as clearly shown in Fig. 2. The 35 shaft of this lever 85 projects past its bearing and has fixed to it the depending arm 86, which also has on it an arm 87 projecting toward the switch or circuit-breaker mechanism with a weight 88 on its end. A 40 pitman 89 is pivoted to the lower part of the arm 86 and has a reduced end part or finger 90 passing through suitable openings in the switch-plate 27, insulating sheet 26 and insulating plate 40, to push against the adjacent side of the rotor 14 when the arm 82 45 swings it in that direction; being normally kept away from this rotor under the action of the weight 88 as well as due to the normal position of the clutch mechanism 80 which 50 controls the swinging of the lever 85 and attached arm 82 due to engagement of the lever 85 in its annular groove. As the machines of this kind are designed, the clutch part 80 moves toward the operator's side of 55 the machine as the loop-setting roller 79 is raised by shortening of the loop 3. Consequently any material shortening of this loop 3 and raising of this roller 79 causes the finger 90 to push the rotor 14, against the 60 yielding pressure of the spring 24, so that the adjacent rotor contact arm 50 is separated from the respective contact face 48 of the contact piece 41. This breaks the circuit and permits the dowser shutter 58 to fall 65 and cut off the heat from the film under

these abnormal conditions. Slight normal changes in tension of the loop do not effect this result; the finger 90 being shortened to permit a slight amount of lost motion.

The moving-picture projecting apparatus 70 illustrated diagrammatically in Fig. 7, is also of a well-known and widely used kind differing from the preceding example in having the film 1' passing over the lower roll or sprocket 2' so that it forms its loop 75 3' on the side next to the lamp house and having its stretch below the roll or sprocket 3' over on the side next to the screen. The film actuating mechanism of this kind of machine is fully enclosed in a cabinet 91 80 which has a side door 92 opening at the operator's side of the machine, with a gap at its front lower corner fitting closely around a stationary part of the side of the cabinet 85 when the door 92 is closed. Our invention 90 is very readily installed in this kind of machine by substituting for this side part, as regularly built into the machine, a modified plate 93 of the same contour and with such details as it must have in conjunction with the regular parts of the machine, as for instance, the opening or bearing 94 in its upper rear corner where the crank is provided for hand operation of the machine. But it 95 will be understood that these machines like those of the other example are variously hand operated or motor operated; and our invention is especially applicable to them when they are motor operated.

This plate 93 has lugs 95 projecting from 100 its front edge and in past its inner side and the switch-plate 27' has one side part screwed to these lugs so that the switch-plate 27' faces inwardly of the machine over toward the shutter 61' thereof. This switch-plate 27' is otherwise identical with the plate 27 of the preceding example, with its provision for admitting the cables and its bearing for the circuit-breaker shaft, and it also 105 has an identical cover 34. The other parts of the circuit-breaker are as in the preceding example; the only exception being that the shaft 18' is not as long as the shaft 18 where it projects out from the bearing of 110 the plate 27'; being merely long enough to carry fixed thereon a segmental pinion 96 in mesh with a segment 97 which forms one end of a rocker arm 98 having its fulcrum 99 fixed in the plate 93 near the front edge 115 thereof at the level of the shaft 18'. There is a bushing 100 around this fulcrum 99 outside the arm 98, and a wire spring 101 is coiled around this bushing and has a member 102 projecting under a projection 103 which the arm has near its segment 97, and another member 104 bearing back 120 against a projection 105 on the face of the plate 93. Where the rocker arm 98 projects back past its fulcrum 99 there is a segmental slot 106 in the plate 93 and this part of the 125

arm has a pin 107 projecting in through this slot. On the inner side of the plate 93 a bell crank has its fulcrum 108 on the level of the shaft 18' and fulcrum 99, and one of its arms 109 projects over and is slotted to receive the pin 107, while the other arm 110 projects down and is pivoted to one end part of a curved link 111, the other end part of which is pivoted to the arm 74' that has a shaft 18'' journaled in the plate 93 near the lower rear corner thereof and projecting out through the front side of the plate 93 and having held on it by means of a set screw, a short arm 112. The upper free end part of this arm 74' carries the stud 76' on which is journaled the idler roller 77' to bear back-wardly against the stretch of the film 1' below the lower roll or sprocket 2'.

The operation of this modified device of this different kind of machine is substantially the same as that of the preceding example; since when the film 1' slackens in the aforesaid stretch and allows the arm to fall back far enough, the connecting mechanism, made up of the link 111, the bell crank, the rocker arm 98, the segment 97 and the segmental pinion 96, will rotate the circuit-breaker rotor until its arms 50 and 51 break contact with the contact pieces 41 and 42; but if there is only slight slackening of the film 1', the motion will be lost by virtue of the arrangement of the pin 19 and recesses 21 as in the preceding example.

35 The spring 101 acts to keep the arm 74' with its roller 77' against the film and to assist this arm 74' in moving the parts to circuit-breaking position when the film slackens. The handle 112 is for manipulating the arm 74' without the necessity of opening the door 92.

40 The electrical connections to the dowser 13 in this modification are the same as in the preceding example, as will be readily understood from Fig. 7.

Other variations may be required under given conditions, and therefore, while certain constructional details are deemed preferable in connection with our invention, and we have shown and described these rather specifically in elucidating the construction and use of our invention, as is required, we do not wish to be understood as being limited to such precise showing and description, but having thus fully described our invention, what we claim as new and desire to secure by Letters Patent is:

45 1. The combination with a moving-picture-machine loop-setter, of an electric switch, and controlling operative engaging means, engaging with said loop-setter and normally spaced from operative engagement with said switch during normal operations of said loop-setter, but operatively engaged with said switch, under actuation by abnormal

operation of said loop-setter, to operate said switch.

2. In combination with a film and film-carrying means, an electric switch, an operative connection to said switch coacting with one part of said film to operate said switch upon abnormal loosening of said part of said film, and an operative connection to said switch coacting with another part of said film to operate said switch upon abnormal tightening of said other part of said film, each one of said operative connections having lost motion whereby normal loosening of said one part or normal tightening of said other part of said film leaves said switch unoperated.

3. In combination with a film, film-carrying means comprising a lower sprocket and a rewinding reel between which part of the film is stretched, said film also having a loop, an electric switch, an operative connection to said switch, supported by said stretched part of said film and operating said switch when said stretched part of said film abnormally slackens, and an operative connection to said switch, engaged by said loop, and thereby operating said switch, when said loop abnormally shortens each one of said operative connections having lost motion whereby normal slackening of said stretched part of said film or normal shortening of said loop leaves said switch unoperated.

4. In combination with a film and film-carrying means stretching part of said film, a shaft journaled adjacent to said part of said film, means fixed on said shaft and extending radially therefrom against said part of said film whereby said shaft is rotated upon change in tension of said film, a contact member turning with said shaft and movable axially of said shaft, contact pieces, means having yieldable pressure on said contact member axially of said shaft to press said contact member against said contact pieces, while said contact member is in one position, said contact member breaking contact with said contact pieces upon rotation of said contact member to another position, engaging means engaged by another part of said film upon change in tension of said other part of said film, and means operatively connected to said engaging means to move said contact member away from one of said contact pieces, against said yieldable pressure, when said engaging means is engaged by said other part of said film.

5. In combination with a film and film-carrying means stretching part of said film, a shaft journaled adjacent to said part of said film, means fixed to said shaft and extending radially therefrom against said part of said film whereby said shaft is rotated upon change in tension of said film, a con-

- tact member turning with said shaft and movable axially of said shaft, contact pieces, means having yieldable pressure on said contact member axially of said shaft to 5 press said contact member against said contact pieces while said contact member is in one position, said contact member breaking contact with said contact pieces upon rotation of said contact member to another 10 position, said film having a loop, a loop-setter for said loop, and means operatively connected to said loop-setter to move said contact member away from one of said contact pieces, against said yieldable 15 pressure, when said loop-setter operates upon shortening of said loop.
6. In combination with a film and film-carrying means stretching part of said film, a shaft journaled adjacent to said part of 20 said film, means fixed to said shaft and extending radially therefrom against said part of said film whereby said shaft is rotated upon change in tension of said film, a contact member rotatably mounted on said 25 shaft and movable axially of said shaft, engaging means whereby said contact member rotates with said shaft during only part of the rotation of the shaft, contact pieces, means having yieldable pressure on said contact 30 member axially of said shaft against said contact pieces while said contact member is in one position, said contact member breaking contact with said contact pieces upon rotation of said contact member to 35 another position, engaging means engaged by another part of said film upon change in tension of said other part of said film, and means operatively connected to said engaging means to move said contact member 40 away from one of said contact pieces, against said yieldable pressure, when said engaging means is engaged by said other part of said film.
7. In combination with a film and film-carrying means stretching part of said film, a shaft journaled adjacent to said part of 45 said film, means fixed to said shaft and extending radially therefrom against said part of said film whereby said shaft is rotated upon change in tension of said film, a contact member rotatably mounted on said shaft and movable axially of said shaft, engaging means whereby said contact member rotates with said shaft during only part of the 50 rotation of the shaft, contact pieces, means having yieldable pressure on said contact member axially of said shaft against said contact pieces while said contact member is in one position, said contact member breaking 55 contact with said contact pieces upon rotation of said contact member to another position, said film having a loop, a loop-setter for said loop, and means operatively connected to said loop-setter to move said contact member away from one of said contact 60 pieces, against said yieldable pressure, when said loop-setter operates upon shortening of said loop.
8. In combination with a film and film-carrying means stretching part of said film, a shaft journaled adjacent to said part of 65 said film, means fixed to said shaft and extending radially therefrom against said part of said film whereby said shaft is rotated upon change in tension of said film, a contact member rotatably mounted on said shaft and movable axially of said shaft, engaging means whereby said contact member rotates with said shaft during only part of the 70 rotation of the shaft, contact pieces, means having yieldable pressure on said contact member axially of said shaft against said contact pieces while said contact member is in one position, said contact member breaking contact with said contact pieces upon rotation of said contact member to another position, one of the contacting surfaces having a sloped terminal part whereby the 75 yieldably pressed contact member breaks its contact with said contact pieces suddenly during said rotation, engaging means engaged by another part of said film upon change in tension of said other part of said film, and means operatively connected to said engaging means to move said contact member away from one of said contact pieces, against said yieldable pressure, when said engaging means is engaged by said other part of said film.
9. In combination with a film and film-carrying means stretching part of said film, a shaft journaled adjacent to said part of 80 said film, means fixed to said shaft and extending radially therefrom against said part of said film whereby said shaft is rotated upon change in tension of said film, a contact member rotatably mounted on said shaft and movable axially of said shaft, engaging means whereby said contact member rotates with said shaft during only part of the 85 rotation of the shaft, contact pieces, means having yieldable pressure on said contact member axially of said shaft against said contact pieces while said contact member is in one position, said contact member breaking contact with said contact pieces upon rotation of said contact member to another position, one of the contacting surfaces having a sloped terminal part whereby the 90 yieldably pressed contact member breaks its contact with said contact pieces suddenly during said rotation, engaging means engaged by another part of said film upon change in tension of said other part of said film, and means operatively connected to said engaging means to move said contact member away from one of said contact pieces, against said yieldable pressure, when said engaging means is engaged by said other part of said film.
10. The combination with a moving-picture-machine and a film operated there- 130

- by with a normally stretched part and a normally slackened part, a switch comprising a rotatable and axially movable contact member, and contact pieces with which respective adjacent parts of said member contact in one position or break contact upon rotation or axial movement to another position, an operative connection having operative engagement with said stretched part 5 of said film and rotating engagement with said member, and an operative connection having operative engagement with said slackened part of said film and axially-moving engagement with said member, upon abnormal stretching or slackening of the respective parts of said film.
11. The combination with a moving-picture-machine and a film operated thereby with a normally stretched part and a normally slackened part, a switch comprising a rotatable and axially movable contact member, and contact pieces with which respective adjacent parts of said member contact in one position or break contact upon rotation or axial movement to another position, an operative connection having operative engagement with one of said parts of said film and rotating engagement with said member, and an operative connection having operative engagement with another one of said parts of said film and axially-moving engagement with said member, upon abnormal changes of tension of the respective parts of the film.
12. The combination with a moving-picture-machine and a film operated thereby with a part susceptible to abnormal changes of tension, a switch comprising yieldably contacting relatively slidable elements, one of which has a terminal part of its contacting surface sloped, and an operative connection having operative engagement with said part of said film and engagement with one of said elements upon abnormal change of said tension to slide one of said elements until the sole contact of said elements is within said sloped terminal part, to cause sudden parting of said elements.
13. The combination with a moving-picture-machine and a film operated thereby with parts respectively susceptible to abnormal changes in tension, a switch comprising yieldably contacting elements one of which is slidable on the other and one of which has a terminal part of its contacting surface sloped, an operative connection having operative engagement with one of said parts of said film and engagement with said slidable element upon abnormal change of the tension of said part, to slide said element until the sole contact of said elements is within said sloped terminal part, to cause sudden parting of said elements, and an operative connection having operative engagement with another one of said parts of said film and engagement with one of said elements upon abnormal change of tension of said part, to cause sudden parting of said elements.
14. In a device of the character described, an electric switch comprising a rotatable axially movable contact member, and contact pieces with both of which respective adjacent parts of said member contact in one position, or break contact upon rotation or axial movement to another position, movable means normally spaced from rotating engagement with said rotatable member, but engaging to rotate said member out of contacting position upon abnormal movement of said movable means, and movable means normally spaced from operative engagement with said contact member, but engaging to move said member axially away from said contact pieces upon abnormal movement of this movable means.
15. In a device of the character described, an electric switch comprising a rotatable axially yieldable contact member, and contact pieces with both of which respective adjacent parts of said member contact in one position or break contact upon rotation or axial movement to another position, movable means normally spaced from rotating engagement with said rotatable member, but engaging to rotate said member out of contacting position upon abnormal movement of said movable means, and movable means normally spaced from operative engagement with said contact member, but engaging to move said member axially away from said contact pieces upon abnormal movement of this movable means.
16. In combination with a film and film-carrying means stretching part of said film, a shaft journaled adjacent to said part of said film, means fixed to said shaft and extending radially therefrom against said part of said film whereby said shaft is rotated upon change in tension of said film, a contact member rotatably mounted on said shaft and movable axially of said shaft, engaging means whereby said contact member rotates with said shaft during only part of the rotation of the shaft, contact pieces, means having yieldable pressure on said contact member axially of said shaft against said contact pieces while said contact member is in one position, said contact member breaking contact with said contact pieces upon rotation of said contact member to another position, said contact pieces and said contact member having the terminal parts of their contacting surfaces sloped, whereby the yieldably pressed contact member breaks

contact with said contact pieces suddenly during said rotation, engaging means engaged by another part of said film upon change in tension of said other part of said film, and means operatively connected to said engaging means to move said contact members away from one of said contact pieces, against said yieldable pressure, when said engaging means is engaged by said other part of said film.

17. In combination with a film and film-carrying means stretching part of said film, a shaft journaled adjacent to said part of said film, means fixed to said shaft and extending radially therefrom against said part of said film whereby said shaft is rotated upon change in tension of said film, a contact member rotatably mounted on said shaft and movable axially of said shaft, engaging means whereby said contact member rotates with said shaft during only part of the rotation of the shaft, contact pieces, means having yieldable pressure on said con-

tact member axially of said shaft against said contact pieces while said contact member is in one position, said contact member breaking contact with said contact pieces upon rotation of said contact member to another position, said contact pieces and said contact member having the terminal parts of their contacting surfaces sloped, whereby the yieldably pressed contact member breaks contact with said contact pieces suddenly during said rotation, said film having a loop, a loop-setter for said loop, and means operatively connected to said loop-setter to move said contact members away from one of said contact pieces, against said yieldable pressure, when said loop-setter operates upon shortening of said loop.
